2,002,500

HIGH-FREQUENCY COUPLING DEVICE

Alfred Crossley and Herbert E. Meinema, Chicago, Ill., assignors to Johnson Laboratories, Inc., Chicago, Ill., a corporation of Illinois

Application April 10, 1934, Serial No. 719,905

4 Claims. (Cl. 171—242)

This invention relates broadly to high-frequency communication systems, and more particularly to receiving systems designed to be operated at communication frequencies, examples being those intended for radio broadcast reception or for carrier reception. Such systems, in general, include, in addition to an antenna-ground system, one or more resonant systems consisting of two inductance coils arranged in magnetic relation to each other, one of the coils being shunted by a variable tuning condenser. The condenser is normally of a type having very low losses, and therefore the efficiency of the complete design depends to a very large extent upon the losses in the inductance coils.

A principal object of this invention is to provide a novel type of coupling means for use in such receiving systems, which, because of its design, will greatly increase the efficiency of the system. This object is attained in part by using iron-cored inductances having new and highly desirable attributes. The cores which we use in these inductances are ferro-magnetic and consist of finely-divided individually-insulated iron particles compressed with a binding material to make a core body. Cores of this type, suitable for use at high frequencies, are disclosed in U. S. Patents Nos. 1,940,228 and 1,982,689, and have recently been described in numerous publications in the United States and abroad. The combination of such a core with a suitable winding is to be designed in accordance with Patent No. 1,978,568, issued Oct. 30, 1934, to Alfred Crossley and Charles C. Neighbors, for Improved high-frequency inductance. The inductance consists essentially of a tubular cylindrical core of the type described, with a pancake universal winding at its center, the length of the winding being usually from three-eights to two-thirds of the radial depth, the length of the core being from 2½ to 5 times the length of the winding.

Still a further object of the invention is attained by so fashioning the insulating frame or support on which the inductance coils and their cores are mounted, that it will constitute a single and integral entity embodying all of the features which are essential to admit of the mounting of the cores and their coils thereon, as well as to enable the frame or support to be itself mounted on an adjacent part of the structure.

Inductances of the class here contemplated normally occur in pairs, one coil being connected in the antenna-ground circuit or in the output circuit of a thermionic relay, and the other coil being connected in the input circuit of a (second) ther-

mionic relay. In order to transfer energy from the first circuit to the second, the coils may be coupled magnetically and thus form a transformer, or they may be coupled capacitively by means of a small condenser connecting their high-potential ends, or a combination of magnetic and capacitive couplings may be used in order to obtain more uniform gain and selectivity over the desired band of frequencies.

The coil in the antenna-ground circuit, or the first thermionic relay output circuit is usually called the primary, and the coil in the input circuit of the (second) thermionic relay is usually called the secondary. In some instances, however, these designations may be reversed, and the thermionic relays may, in certain types of apparatus, be arranged so that they do not operate strictly as amplifiers. These variations, however, are not material with respect to the application and scope of the present invention. The variable tuning condenser is usually shunted across the coil here designated as the secondary coil.

In present-day designs, coupling devices of the class here under consideration normally employ two magnetically coupled air-core inductances. By suitably designing the primary and secondary windings, and by adjustment of the tuning condenser, the system may be tuned to be resonant at the desired frequency. In order to effect a maximum transfer of energy between the primary and the secondary, it is essential that the magnetic coupling between the two windings shall be closely of the optimum value. In present designs, it is normal to establish the degree of coupling in the design of the transformer, so that when the coils are assembled the proper coupling will exist.

Because of the losses which normally exist in air-core coils of the type now commonly used, it is not essential to provide means for adjusting the coupling between the primary and secondary coils after the unit is assembled. It is usually sufficient to determine experimentally what physical relation between the two coils will give approximately the correct coupling and then to mechanically design the coupling device so as to produce this relation.

In the designs herein described, the losses in the coils themselves are greatly decreased, and it therefore becomes desirable to provide means for accurately adjusting each coupling device to the desired coupling between primary and secondary. The present invention, therefore, includes designs employing coils having greatly increased efficiency, and arrangements whereby

two such coils may be magnetically related in a coupling device with means for producing an accurate adjustment of the magnetic coupling between the windings.

5 Because of the higher efficiency of iron-core coils, it is possible to obtain greater energy transfer with less coupling than is permissible with air-core coils. This results in an increase in the electrical efficiency of the coupling device. For 10 example, one embodiment of the invention uses about 20% magnetic coupling between the coils and a coupling condenser of 8.5 micromicrofarads. When used with a 200-micromicrofarad antenna, this antenna coupling device gives a 15 gain of about 20 in comparison with a gain of about 9 obtainable with air-core coils, at frequencies between 550 and 1500 kilocycles.

The invention will be better understood by reference to the accompanying drawing, which is 20 illustrative of one possible mechanical embodiment of the invention and in which—

Fig. 1 is an elevation of a high-frequency coupling device employing ferro-magnetic core bodies;

25 Fig. 2 is a bottom view of the coupling device shown in Fig. 1;

Figs. 3 and 3a present simplified schematic wiring diagrams which illustrate methods of employing the coupling device of this invention in 30 the circuits of a high-frequency receiver.

Referring to Fig. 1, the coupling device here 35 illustrated consists of a flanged insulating base 1, preferably of a molded phenolic compound such as bakelite. The base 1 is designed to be conveniently secured to the receiver chassis 2 by 40 means of the non-magnetic threaded stud 3 and the nut 4, said stud 3 being preferably molded into the base 1. A spindle 1a, preferably consisting of a molded phenolic compound, such as 45 bakelite, receives the hollow cylindrical ferro-magnetic core 5 of the primary winding 6, and the hollow cylindrical ferro-magnetic core 7 of the secondary winding 8. These cores are held firmly in place by a suitable cement 9, and may 50 be adjacent each other or be spaced a suitable amount to approximate the desired degree of coupling.

For use in the frequency band between 550 and 1500 kilocycles, the primary coil 6 for an 55 antenna coupling device may have an inductance of about 1.25 millihenries and be resonant with a normal 200 M. M. F. antenna at a frequency below the desired band of frequencies, as, for example about 315 kilocycles, thereby producing the minimum effect on the gain within the 60 desired band of frequencies. If the device is to be used to couple two thermionic relays, the primary inductance may be about 3.2 millihenries. The secondary coil 8 in either type may have an inductance of about 250 microhenries so as to 65 cover the desired band of frequencies when tuned by a variable condenser having a maximum capacity of about 365 micromicrofarads. The cores 5 and 7 are secured to the spindle 1a by means of any suitable cement.

In the embodiment here shown, it will be noted 70 that the core 5 of the primary coil 6 is smaller than the core 7 of the secondary coil 8. Since the secondary coil is a component of a tuned circuit, it is desirable to keep its losses as low as possible. Hence a relatively small coil on a relatively large core is used. The primary coil, however, is untuned, and its losses may be higher without serious effect. Hence for the sake of 75 economy a relatively large coil on a relatively

small core is used. This choice may be found advantageous in those cases where cost is an important consideration.

Referring to Figs. 1 and 2, terminals 10 extend 5 downward from the base 1, being preferably eyeleted through square holes in the base 1. Each lead 11 from the coils 6 and 8 extends through an eyelet and is soldered to a terminal 10. Coupling condenser 12 is mounted underneath the base 1 by soldering it to the two terminals 10 which 10 connect to the high-potential ends of the coils 6 and 8. This condenser may have a capacity of 15.0 micromicrofarads for an interstage coupling device intended for use with thermionic relays 15 in the frequency band between 550 and 1500 kilocycles. In this case, about 8% magnetic coupling is satisfactory, and may be obtained by spacing the cores 5 and 7 a short distance apart.

Referring again to Fig. 1, the assembly may 20 include a metal shield 13 which is usually desirable in order to prevent electro-magnetic and electrostatic coupling between adjacent coupling devices. The shield 13 may be arranged to be eyeleted or otherwise suitably secured to the chassis 2. The metal chassis 2 of the receiver 25 completes the shielding of the coupling device.

Fig. 3 shows a coupling device of the type herein contemplated connected between an antenna-ground system 14 and the input circuit 15 of a thermionic relay 16. The primary coil 6 is connected between the antenna and ground. The secondary coil 8 is connected in parallel with the variable condenser 17 to form a resonant circuit in the grid circuit of the thermionic relay 16.

Fig. 3a shows a coupling device of the type 35 herein contemplated connected between the output circuit 18 of the thermionic relay 19 and the input circuit 15 of the thermionic relay 16. The primary coil 6 is connected in series with the anode of the thermionic relay 19. The secondary 40 coil 8 is connected in parallel with the variable condenser 17 to form a resonant circuit in the grid circuit of the thermionic relay 16.

A combination of magnetic and capacitive coupling is especially desirable in coupling devices 45 designed for use over a band of frequencies, since it gives much more uniform gain and selectivity than could be obtained with either magnetic or capacitive coupling alone. Capacitive coupling between the primary and secondary circuits is obtained by means of the condenser 12. The exact 50 degree of magnetic coupling obtained is determined by the relative positions of the cores 5 and 7 and their respective coils 6 and 8, and may be adjusted after assembly but before the cores 5 55 and 7 are cemented to the spindle 1a, by sliding the core 7 axially up or down.

In employing transformers in accordance with 60 this invention in the antenna stage of broadcast receivers, it is preferable to so connect them that the magnetic coupling and the capacitive coupling 65 will be additive. In interstage uses, however, the connections are preferably such that the magnetic and the capacitive couplings are in opposition.

Certain specific design data and constants have 70 been given to complete the description of the present invention. It should be understood, however, that these constants are mentioned merely by way of example in describing certain specific embodiments which in practice have proved satisfactory, and are not intended to suggest any specific limitations as to the scope of this invention.

Having thus described our invention, what we 75 claim is:

1. A high-frequency coupling device including a concentrated primary winding and a concentrated secondary winding, a ferro-magnetic core for each of said windings, said primary winding having a natural frequency lower than any frequency to which said secondary winding is intended to be tuned, said cores being adjacently and coaxially disposed and relatively adjustable, whereby the electro-magnetic coupling between 5 said primary winding and said secondary winding may be conveniently adjusted to any desired value within the range of said device.
2. A high-frequency coupling device including a central insulating post, a flange extending radially from said post, compressed comminuted ferro-magnetic cores mounted upon said post, a primary winding mounted upon one of said cores, a secondary winding mounted upon another of said cores, said primary winding having 10 a natural frequency lower than any frequency in the range through which said secondary is intended to be tuned.
3. A high-frequency coupling device including two coils wound upon and secured to compressed comminuted tubular magnetic cores, said cores being mounted coaxially upon a mandril having an insulating radial flange with terminals adapted to be connected to the ends of said coils, one of said coils having a natural frequency lower than any frequency to which the other coil is intended to be tuned. 15
4. A support for the ferro-magnetic cores and the terminals of a high-frequency transformer in a signaling device, including a horizontal disc having perforations into which said terminals may be secured, an integral downwardly extending post having inserted therein a metal stud for securing said support to the frame of said signaling device, and a separate upwardly extending insulating post for coaxially supporting said cores. 20
